UNITED STATES PATENT OFFICE

ROBERT L. LYONS, OF WALTHAM, MASSACHUSETTS, ASSIGNOR TO AMERICAN BUTTON SEWING MACHINE CO., OF BOSTON, MASSACHUSETTS, A CORPORATION OF MASSACHUSETTS

SEWING MACHINE

Application filed February 20, 1931. Serial No. 517,223.

This invention relates to sewing machines, and while certain of the desirable features of the invention are not limited thereto, it is particularly suitable to machines for the sewing of four hole buttons or the like, using two needles, each forming chain stitches, the two sets of stitches being entirely independent of each other so as to present on the back face of the work two parallel spaced lines of 10 stitches.

One object of the invention is to insure proper cooperation between the needles and oscillatory loopers to prevent the possibility of stitches being missed, and regardless of 15 the relative movement of the button and needles, to hold the loops of thread on the loopers in each needle path.

A further object is to provide an improved control of the thread loops whereby they cannot become caught by any part of the stitch-forming mechanism and which gives time for proper operation of certain of the parts.

A still further object is to provide a support for the work which will permit buttons 20 to be sewed to soft material satisfactorily.

Another object is to provide a machine of this type wherein the needles are so positioned as to permit ready threading.

A further object is to provide such a machine in which the movements of the parts shall not tend to pull or push the button out 25 of its holding means.

A still further object is to provide a machine having in the one organization the desirable attributes of both a flat top and a horn machine.

Further objects will be apparent from a more complete description of an embodiment of the invention shown in the accompanying 30 drawings in which

Figure 1 is a side elevation of a button sewing machine embodying this invention.

Figure 2 is a front elevation of the sewing head showing the needle bar in raised position.

Figure 3 is a horizontal section on line 3—3 of Figure 1.

Figure 4 is an inverted plan of the machine.

Figure 5 is a fragmentary plan of the cloth 35 plate.

Figure 6 is a fragmentary section to a larger scale on line 6—6 of Figure 4.

Figure 7 is a view somewhat similar to a portion of Figure 4 but to a larger scale.

Figures 8 and 9 are sections on lines 8—8 and 9—9, respectively, of Figure 6.

Figures 10 and 11 are sectional views somewhat similar to Figure 9, but showing a button being sewed and with parts in successive 40 positions in the stitching cycle.

Figure 12 is a detail inverted plan showing the thread finger.

Figures 13 to 16 inclusive are diagrammatic views showing the relative positions of certain of the sewing instrumentalities 45 during successive portions of the stitching cycle, the button, needle and looper mechanism being shown enlarged relative to the needle bar and related mechanism for the 50 sake of clarity.

The machine illustrated in the drawings comprises a bed 1 having a post 2 upstanding from its rear end terminating in a forwardly extending sewing arm 3 provided with the usual sewing head 4. As shown best in 55 Figures 3 and 4, the bed 1 is provided with a forwardly extending central horn portion 5 within which are housed certain of the stitch forming mechanism, as will later appear.

On either side of this horn portion are parallel spaced portions 6 which form additional work supporting members which cooperate 60 with the horn 5 to form in effect a relatively wide work table for supporting relatively 65 heavy work. In the case of lighter work or where buttons are to be sewed to sleeves, or the like, the work may be applied to the horn portion only, passing through the slots 7 which separate the horn portion 5 from 70 the portions 6. One or both of these portions 6 may, if desired, be provided with depressed pockets as 8 in their upper faces 75 which may be used to hold buttons in convenient position for the operator.

At 10 beneath the bed 1 is shown the main rotary driving shaft of the machine. Driven from this shaft, as by means of the double cranks 11 and 12 and the crank rods 13, is the needle bar actuating shaft 14 which acts 100

to impart work piercing and retracting strokes to a needle bar 15 mounted for vertical movement in the head 4. As shown the reciprocations of the needle bar are produced from rotation of the shaft 14 by means of a crank 16 fixed to the shaft 14 and a link 17 extending from the crank to a pivot 18 on a sleeve 19 fixed to the needle bar. At 20 is shown a variable thread tension mechanism actuated by a suitable cam 21 on the shaft 14 so as to lock the thread supply when the cast off thread loops are being pulled up against the work by the motion of the needle bar. At 22 is shown a constant tension. 15 The needle bar 15 has secured thereto a pair of needles 25 arranged in a plane extending from front to back of the machine. Cooperating with these needles to form stitches are the mechanisms within the horn portion 5 including, the oscillatory loopers shown best in Figures 6 at 26, these being fixed to an oscillatory shaft 27. This shaft is oscillated in time with the motions of the needle bar by the rotation of the main shaft 10, this shaft carrying a cam 30 thereon provided with a face groove 31 within which rides a follower 32 carried by an arm 33 fixed to the looper shaft 27. The greater portion 20 of the groove 31 is concentric with the shaft 10 but the groove has a reentrant portion 34, which, when in engagement with the follower 32, causes a quick oscillation of the loopers. It will be noted from an inspection of Figure 6 that the loopers face in 25 the same direction and that this direction is such as to require the threading of both needles from the same direction and from the front of the machine. This is a distinct advantage in a multiple needle machine since 30 it is found in practice that where the needles must be threaded in opposite directions there is considerable danger of unthreading one when it is attempted to thread another. Moreover, it is most convenient to the operator if the threading can be accomplished 35 from the front of the machine.

Since, as will later appear, the work is given motions alternately in opposite directions to present successively alternate holes 50 of a pair in the button in the path of each needle, means are necessary in order to present the loops of thread taken by the loopers in position for the needles to pass therethrough on their next succeeding work piercing stroke. The cam 30 is herein shown as utilized for the purpose of giving the necessary motions to such means which comprises a single thread finger taking the loops from both of the loopers. To this end the cam 30 55 is shown as provided with a peripheral groove 40 within which rides a cam follower 41 fixed to a block 42. This block is carried by a slide 43 and extends through a slot 44 in a plate 45, the slide 43 riding in a guide 60 groove 46 in the upper face of the plate 45, 65

as shown best in Figure 8. A screw 47 threaded into the slide 43 and passing through an elongated slot 48 in the plate 45 acts as a further guide to the motion of the slide 43. Near its forward end this slide 43 has pivoted thereon, as by the screw 50, with a washer 51 interposed therebetween, a thread finger 52. A friction washer 53 beneath the head of the screw 50 tends to hold the thread finger frictionally in any angular position to which it may be turned. This thread finger 52 is provided with a finger portion 54 having adjacent to its free end a pair of spaced notches 55 and 56 in one edge. Each of these notches is formed with a substantial shoulder portion 57 on that side only which is the more remote from its free end so that the finger can be withdrawn endwise from the loops freely but may engage the thread loops and hold them in proper longitudinal position spaced apart and in the proper position for the respective needles to pass therethrough. The thread finger is also provided with a tail portion 60 which extends between a pair of eccentric abutments 61 and 62. As the slide 43 is moved from front to back, this tail 60 engages alternately on the abutments 61 and 62, whereupon further movement of the slide 43 causes a quick lateral movement of the finger portion to engage or release the loops of thread from the loopers. Adjustment of the angular positions of the abutments 61 and 62 adjusts the timing of this lateral motion to a limited degree. 70

The work holding mechanism comprises a button clamp 70 of conventional form and a cloth plate 71 therebeneath. The button clamp is shown as pivoted at 72 (see Figure 1) and may be raised from the upper face of the cloth plate at the end of the sewing 100 operation to break the threads by any suitable means. As herein shown this is accomplished by a chain 73 attached at its lower end to a suitable portion of the button clamp and at its upper end to an arm 74 carried by a 105 rock shaft 75. This rock shaft may be turned to lift the clamp by exerting a downward pull, by a treadle or other suitable means (not shown), on a chain 76 attached to an arm 77 fixed to the rock shaft 75. A spring 78 normally holds the button clamp lowered. The button clamp, as shown best in Figure 3, comprises a pair of spaced side jaws 80 and 81 and a rear central jaw 82 which support the button therebetween, the button being inserted or removed by a motion front to back of the machine through the forward open end of the clamp between the side jaws 80 and 81. Any suitable means may be provided for retracting the jaws to permit adjusting the 110 normal spacing of the jaws in accordance with the size of the button, but as these are usual in the art no description is believed necessary. 115

The button clamp and the cloth plate to- 120

gether are given a motion laterally of the plane of the two needles and as the two needles are arranged in a plane from front to back of the machine, this motion of the work holding mechanism is also laterally of the machine. This motion may be produced by any suitable means, but as herein shown it is produced by means of a cam 90 adjustably carried at the lower end of a vertical shaft 91 which is driven from the main drive shaft 10 as by the gearing at 92. This cam 90 has a cam groove 191 in its upper face within which rides a follower 192 on an arm 93. This arm 93 is carried by a vertical shaft 94 which extends upwardly through the top of the base 1 and has fixed thereto a grooved segment 95. Adjustable in the groove 96 of this segment is a pivot member 97 at one end of a link 98, the other end of which is pivotally connected at 99 to a support 100 to which both the button clamp and the cloth plate are attached. By this means the cloth plate and button clamp are vibrated laterally in unison and to the desired extent between successive sewing strokes of the needles.

As shown in Figure 5 the cloth plate is provided with a pair of slots 105 for the passage of the needles, the portion 106 between the slots acting as a support for the material which prevents it from being drawn down into the needle holes during the work piercing strokes of the needle. One of the advantages of this machine is that it permits the use of such a work supporting bridge across the throat through which the needles pass, as in many cases it has been found impossible to use a single needle machine for sewing on buttons, particularly near the edge of relatively soft material, as the single needle machine requires an opening for the needle to pass of sufficient size to include all four needle holes of the button, since the needle must pass through each of these holes. Where such a large opening is provided soft material may be drawn down into the hole to a sufficient extent to seriously interfere with even if it does not prevent the sewing operation. Where it is possible, as in the two needle construction herein illustrated to support the work between the needles, the downward pressure of the needles is exerted on opposite sides of the support simultaneously so that the tendency of either needle to displace the material and project it through the needle holes in the cloth plate is substantially nullified by the action of the other.

In order to provide for proper control of the loops of thread cast off by the looper hooks so that they may not be caught by these hooks on the next succeeding stroke and yet to permit the needles to be withdrawn freely from the cast off loops, an improved loop control mechanism has been developed. Such a loop control is applicable to a single

needle machine as well as to a two needle machine and for the sake of clarity but a single thread has been illustrated in Figure 2 and Figures 13 to 16 inclusive. The needle thread after passing beneath the constant tension 22 and the guide 110 passes through a perforation 111 in the upper portion of the needle bar. From this it passes about a guide 112 adjustably secured to the needle bar and extending out through a slot 113 in the forward face of the sewing head 4. After passing about this guide the thread passes about another guide 114 mounted in fixed position on the forward face of the sewing head 4 at one side of the slot 113. After passing about this guide 114 the thread extends to its needle eye. The thread guide 114 is positioned adjacent to the path of motion of the guide 112 as the needle bar is reciprocated so that the guide 112 passes the guide 114 before the needle bar reaches the lower limit of its stroke.

Referring now to Figures 13 to 16, the relative positions of the needle bar for successive corresponding positions of the looper are illustrated. When the needle bar is in its downward stroke at the point shown in Figure 13, the guide 112 is in horizontal alignment with the guide 114, the looper hook 115 extends through a loop of thread from the needle and the thread finger 52 is holding this loop 116 in position for the needle to extend therethrough. As the needle bar continues to descend to the position shown in Figure 14, the looper hook 115 moves backwardly casting off the loop 116 over the needle 25 and the finger 52 is retracted. This downward motion of the needle bar also causes the thread to be pulled back between the guides 112 and 114 so that the loop 116 is partly pulled up so that it is too high for the looper hook 115 to engage it on its succeeding forward motion, at which time it engages and takes the next succeeding needle loop, but the loop is not drawn up sufficiently to engage tight about the needle. In Figure 14 the position of the needle bar is shown at substantially its limit of downward motion. As it is then retracted toward the position shown in Figure 15 the needle is entirely withdrawn from the loop 116 before the guide 112 reaches a position shown in Figure 16 above the guide 114 equal to the distance it moved below the guide 114 in its downward stroke, this providing a dwell in the pull back of the thread sufficient in extent for the needle to be retracted entirely from the loop 116 before the loop is pulled up against the lower face of the work. As soon as the needle bar has been raised sufficiently to cause the guide 112 to be as far above the guide 114 as it was previously moved below the guide 114, as shown in Figure 16, upward movement of the needle bar again exerts a pulling action on the loop so that in its extreme raised

position the loop 116 has been set up firmly against the lower side of the work. At this time the hook 115 has moved forwardly again and has taken the last needle loop so that the 5 parts are in the position shown in Figure 15. The lateral motion of the work holder also assists in drawing the loops up against the work. Figures 13, 14 and 15 show the work holding mechanism in its right hand position 10 and Figure 16 shows the button clamp and cloth plate as having been moved over to the left and with the thread finger 52 holding the thread loop in position for the needle 25 to pass therethrough as it passes downward 15 through the right hand hole of the pair in the button although in this position of the button clamp the thread finger is not absolutely necessary to hold the loops in proper position for the needles to pass therethrough. The 20 loopers and needles are thus caused to operate irrespective of the relative lateral position of the button and work and the needles.

Where the work is vibrated from and toward the looper axis as in this machine, each 25 loop formed when the work is nearest to the looper axis, as in Figure 13, is longer than the loops formed in the other position of the work as shown in Figure 15, and the loop 30 drawing mechanism must have a stroke of sufficient length to draw up the longer loop, and the longer loops must be drawn up further to escape the looper hooks on their succeeding loop-taking movements. In this machine, therefore, it is necessary to effect a 35 quick preliminary drawing movement to pull up the cast loops sufficiently to escape the looper hooks, and then to delay the complete tightening of the loop to permit the needle 40 to withdraw therefrom. This delay is particularly necessary where the shorter loops are being drawn since because of their shorter length they would be tightened up earlier than the longer loops. This action is provided for in the present construction by the 45 two drawing actions with an intermediate dwell. During the second loop-tightening stage the work is given its vibrating movement.

50 From the foregoing description of one embodiment of this invention it will be apparent to those skilled in the art that various changes and modifications might be made without departing from the spirit or scope 55 of this invention as defined by the appended claims.

I claim:

1. The combination in a button sewing machine, of a needle, and an oscillatory looper 60 for taking successive loops of thread from the needle and casting off said loops about the next succeeding needle loop in chain stitch formation, and means for vibrating the work between successive needle strokes laterally of 65 the needle, said machine including means for

drawing the cast-off loop out of the way of the looper at its succeeding loop-taking stroke but loosely about said needle before the retracting stroke of said needle and completing the drawing of said cast off loop 70 against the work beneath the button only after the needle has been withdrawn therefrom.

2. The combination in a button sewing machine, of a needle bar, a needle carried by 75 said bar, and an oscillatory looper for taking successive loops of thread from the needle and casting off said loops about the needle and the next succeeding needle loop in chain stitch formation, and means for vibrating 80 the work between successive needle strokes laterally of the needle, said machine including means for drawing back the cast off loop in two stages with a dwell therebetween during which dwell the needle is withdrawn 85 from said cast off loop.

3. The combination in a button sewing machine, of a needle bar, a needle carried by said bar, an oscillatory looper for taking successive loops of thread from the needle and casting off said loops about the needle and the next succeeding needle loop in chain stitch formation, means for vibrating the work between successive needle strokes laterally of 90 the needle and means including said needle bar for drawing back the cast off loop in two stages with a dwell therebetween during which dwell the needle is withdrawn from 95 said cast off loop.

4. The combination in a button sewing machine, of a sewing head, a needle bar reciprocable in said head, a needle carried by 100 said bar, an oscillatory looper for taking successive loops of thread from the needle and casting them off over the needle and the next succeeding needle loop in chain stitch formation, a stationary thread guide on said head adjacent to said bar and from which the thread passes to said needle, and a thread 105 guide on said needle bar about which the thread passes before passing to said fixed guide, said guides being positioned for said needle bar guide to pass said fixed guide to cause an initial pull back of the cast off loop 110 on the last portion of the work piercing stroke of said needle bar to remove said cast off loop from the path of the looper, to cause a dwell on the initial portion of the retraction of said needle bar during which the needle is withdrawn from said cast off loop, and then to complete the pull back to tighten 115 said cast off loop against the work beneath the button.

5. The combination in a button sewing machine, of a needle bar, a pair of needles carried by said bar spaced to pass through pairs of holes in the button, an oscillatory looper shaft, a looper for each needle fixed to said shaft for taking successive loops of thread 120 from its respective needle and casting off each 125

- of said loops about its needle and the next succeeding needle loop in chain stitch formation, and means for drawing back the cast off loops from all the needles in two stages 5 with a dwell therebetween during which dwell each needle is withdrawn from its respective cast off loop.
6. The combination in a button sewing machine, of a needle bar, a pair of needles carried by said bar spaced to pass through pairs of holes in the button, an oscillatory looper shaft, a looper for each needle fixed to said shaft for taking successive loops of thread from its respective needle and casting off 10 each of said loops about its needle and the next succeeding needle loop in chain stitch formation, and means including said needle bar for drawing back the cast off loops from all the needles in two stages with a dwell, 15 therebetween during which dwell each needle is withdrawn from its respective cast off loop.
7. The combination in a button sewing machine, of stitch forming mechanisms including two reciprocating needles and an oscillating looper for each needle, work holding mechanism including a button clamp having spaced jaws between which a button may be inserted by movement in one direction, and means for vibrating said clamp between 20 stitch formations at right angles to said direction to bring two holes of a button held by said clamp alternately in the path of each of said needles.
8. The combination in a button sewing machine, stitch forming mechanisms including a pair of reciprocating needles, a looper movable about an axis for each of said needles and a thread finger for taking the loops from both loopers and presenting them 25 in position for the needles to pass therethrough on their next succeeding stroke, and work-holding mechanism including a button clamp having an opening for the insertion and removal of a button by movement in opposite directions, said loop presenting movements of the thread finger being at right angles to the direction of insertion and removal of a button relative to said clamp.
9. In a multiple needle button sewing machine, a needle bar, a pair of needles carried by said bar, a button clamp having an opening for the insertion and removal of buttons, an oscillatory looper shaft arranged substantially parallel to the line of insertion and 30 removal of buttons from said clamp, a looper for each needle on said shaft, and a thread finger cooperating with the thread loops on said loopers and moving them at right angles to said looper shaft.
10. In a multiple needle button sewing machine, a needle bar, a pair of needles carried by said bar in a plane arranged from front to back of the machine and spaced to pass through pairs of holes in the button, and a looper for each of said needles, all of said 35 loopers facing in the same direction and in position to require the threading of all the needles from the front of the machine.
11. In a multiple needle button sewing machine, a needle bar, a pair of needles carried by said bar in a single plane and spaced to pass through pairs of holes in the button, an oscillatory looper shaft arranged parallel to the plane of said needles, and a looper for each needle on said shaft, said loopers being arranged symmetrically with relation to their respective needles in position to require both needles to be threaded from the same side. 40
12. In a multiple needle button sewing machine, a needle bar, a pair of needles carried by said bar in a single plane arranged from front to back of the machine and spaced to pass through pairs of holes in the button, an oscillatory looper shaft arranged parallel to the plane of said needles, and a looper for each needle on said shaft, said loopers being arranged symmetrically with relation to their respective needles and in position to require threading of both needles from the front of the machine. 45
13. In a chain stitch button sewing machine, a needle bar, a pair of needles carried by said bar spaced to pass through pairs of holes in the button, a looper shaft, a looper on said shaft for each needle to take successive loops of thread from its respective needle, and a single thread finger for taking all the loops engaged by the loopers after said needle bar has retracted to hold said loops in position for the needles to pass therethrough in the succeeding work piercing needle strokes. 50
14. In a chain stitch button sewing machine, a needle bar, a pair of needles carried by said bar spaced to pass through pairs of holes in the button, a looper shaft, a looper on said shaft for each needle to take successive loops of thread from its respective needle, and a single thread finger for taking all the loops engaged by the loopers after said needle bar has retracted to hold said loops in position for the needles to pass therethrough in the succeeding work piercing needle strokes, 55 said finger having means for holding each loop in a definite position thereon.
15. In a chain stitch button sewing machine, a pair of needles, a button holder, a looper for each needle, means for producing vibratory motions between said needles and holder laterally of the needles, and a thread finger for positioning threads from said loopers in proper position to said needles irrespective of the relative lateral positions of said holder and needles and having a thread-receiving notch in one edge for each needle and looper. 60
16. In a chain stitch button sewing machine, a pair of needles, a button holder, a looper for each needle, means for producing vibratory motions between said needles and holder laterally of the needles, and a thread 65

finger for positioning threads from said loopers in proper position to said needles irrespective of the relative lateral positions of said holder and needles, said finger having a free end and a pair of notches in one edge each to receive loops of thread from one of said loopers and present them in proper rela-

tion to one of said needles, that side of each notch the more remote from said free end presenting a pronounced shoulder for engagement with its respective loops.

In testimony whereof I have affixed my signature:
